UNITED STATES PATENT OFFICE.

CHARLES STUPIAN, OF BUFFALO, NEW YORK, ASSIGNOR TO CARMINE PETRILLO, OF BUFFALO, NEW YORK.

PASTRY-BAKING MACHINE.

1,119,548.

Specification of Letters Patent.

Patented Dec. 1, 1914.

Application filed March 11, 1912. Serial No. 682,870.

To all whom it may concern:

Be it known that I, CHARLES STUPIAN, a subject of the King of Hungary, residing at Buffalo, in the county of Erie and State 5 of New York, have invented certain new and useful Improvements in Pastry-Baking Machines, of which the following is a specification.

My invention relates to pastry-baking machines of that class having mold members or dies in which pastry cones, cups, or other hollow articles are molded and baked.

The primary object of my invention is to provide a machine of that class in which provision is made for bringing the die members together by a rectilinear movement of at least one of said members, so that the batter will be forced equally in all directions from a center line, thereby assuring a 20 finished product having its wall of equal thickness at every point.

Another object of my invention is the production of a machine by means of which hollow pastry articles can be produced at 25 minimum cost with increased facility and more conveniently than heretofore, and to apply the heat so that the articles will be baked evenly throughout from both inside and out.

30 Further objects are the provision of improved means for facilitating the removal of the hollow articles from the die-members, and to otherwise improve on machines of this class now in use.

35 My invention consists of the combination with a plurality of cores or male dies, of a plurality of female dies toward and into which the male dies are movable in rectilinear lines and which female dies are composed of sections relatively movable at right angles to the movement of said cores or male dies.

40 It also consists in the provision of novel means for separating the sections of the female dies; in the provision of a heating device in operative relation to said female dies and in a heating device movable with said cores or male dies.

45 It further consists in a plurality of male and female dies relatively movable in vertical planes; in the provision of means for automatically cutting off the heat from the female dies when separated from the cores or male dies, and in the novel features of

construction and the arrangement and combination of parts to be hereinafter described and more particularly pointed out in the subjoined claims.

In the drawings.—Figure 1 is a side elevation of a machine embodying my invention in a representative form. Fig. 2 is an end elevation of the same. Fig. 3 is a horizontal section taken on line $v-v$, Fig. 1. Fig. 4 is a vertical section taken on line $w-w$, Fig. 3. Fig. 5 is an enlarged vertical section taken on line $x-x$, Fig. 3, showing also in sectional view the continuation of the support used in connection with the machine. Fig. 6 is an enlarged vertical section through a portion of the male die member and its supported burner. Fig. 7 is a horizontal section taken on line $y-y$, Fig. 1, and Fig. 8 is an enlarged transverse section taken on line $z-z$, Fig. 3.

Referring now to the drawings in detail, 75 like characters of reference refer to like parts in the several figures.

The reference letter A indicates a frame which is preferably rectangular in formation and supported upon suitable legs a , so 80 as to hold the frame elevated. Arranged within said frame is one or more die members B, there being three shown in the particular machine illustrated. These die members may be termed the female die members 85 since in them are formed concavities b of such formation as the finished product is to have. Each die member has two longitudinal series of such concavities and is formed of three sections, C, D, E. The inner faces of the outer sections C, E, having one-half of a longitudinal series of concavities formed therein, and the two sides of the intermediate section D having the remaining half of said longitudinal rows of concavities; in other words, the female die member is separable centrally through the concavities therein. It is apparent, however, that the arrangement of the concavities may be departed from that herein 95 shown. The female die members B are supported on a pair of longitudinal guide-rods 100 F fastened into opposite ends of the frame and these rods serve as guides upon which the two outer sections of each member are guided for movement toward and from their co-operating intermediate section. Said intermediate sections are held against move-

105

ment on the guide-rods F by means of shafts G arranged at right angles to the guide-rods F and passing longitudinally through the intermediate sections, said shafts being journaled in the opposite side walls of the frame A, as at g.

Arranged at opposite ends of each female die member are double levers H, which are fastened centrally to the shafts G and pivotally secured to opposite ends of each lever are links I, which are connected to studs i extending from the ends of the outer sections of each female die member. Secured to the shafts G are gear wheels J, which are 15 preferably arranged outside of the frame A, and in the particular embodiment of my invention herein shown, these gear wheels are arranged in train, so that the intermediate gear wheel is in mesh with the end gear 20 wheels. Secured to the center shaft G is an operating lever K and extending from said operating lever is an arm k having passed therethrough an adjusting screw L to one end of which is secured one end of a 25 retractile spring l which has its outer end fastened to a fixed point of the frame A.

As an additional guard to prevent movement of the intermediate section of each female die member on the guiderods F, bolts 30 M are passed through the side walls of the frame A and threaded into opposite ends of said intermediate sections. By this means, said intermediate sections are held so as to prevent lateral strain on the shafts G and 35 thus assure freedom in action without tendency to bind.

Arranged beneath the female die members is a gas burner or other heating device N having jets n so located as to be positioned 40 directly beneath the concavities in the female die members, a suitable fuel supply pipe O leading to the burner, as is common.

Rising from the frame A are combined supports and guide rods P, to the upper end 45 of which is secured a second frame p, and mounted on bearings on said frame is a shaft Q having secured thereon a pair of gear wheels q and having also fastened to one of its ends an operating wheel R and a 50 sheave r, for a purpose to appear herein-after.

S represents a male die member which is guided for movement on the vertical guide rods or supports P and comprises a plate s 55 having openings T therein and male dies or cores t fastened to the underside of said plate, said male dies or cores are of a shape to correspond to the concavities in the female die members but are made a trifle smaller than said concavities and they are 60 also made hollow with the opening in the plate s registering with the interior of said dies or cores. These male die, or cores are positioned centrally with respect to the concavities of the female die members and when

lowered enter said concavities. Rising from the male die members are two gear racks U, which are held in mesh with the gear wheels q on the shaft Q, and supported on said die member is a burner or other heating device V 70 having jets v directed downwardly into the hollow male dies or cores. The flames from the burners N and V play, respectively, against the under sides of the female die members directly beneath all the concavities 75 therein and against the interior surfaces of the hollow male dies or cores. Connected to the burner V is a supply-pipe W to which may be attached a hose so that the male die member can be raised and lowered without 80 interfering with the supply of the fuel.

Wound around the sheave r is a cord or cable X which is directed downwardly for connection to one end of a baffle plate x. This baffle plate passes through a slot Y 85 formed in one end wall of the frame A and receives support from rollers y fastened rotatably to tracks Z extending from the wall of the frame A having the slot Y therein to the opposite wall and being secured to both. 90 Said cord or cable X passes around a sheave z journaled in a bracket secured to the frame A.

Adjacent the frame A is a frame 10 from which rises an arm 11 having a pulley 12 at its upper end, and secured to the baffle plate x is a cord or cable 13, which passes around a pulley 14 on frame 10 and also around the pulley 12, thence downward from the latter, and to the end thereof is attached a 100 weight 15. On the frame 10 are placed a plurality of supporting rollers 16 on which the baffle plate x rides when drawn outward from the frame A.

The operation of the device is as follows:—The batter used for baking the cones or other hollow articles is poured into the concavities b in the required quantities, after which the operator lowers the male die member with its supported heating-device by 105 rotating the shaft Q, thus bringing the male dies or cores centrally into the concavities of the female die members and spreading the batter between said male die members or cores and the walls of said concavities. The rotation of the shaft Q unwinds the 110 cord or cable X from the sheave r, thus allowing the weight 15 to gravitate and cause the baffle plate x to be withdrawn from the frame A. This permits the heat of the burner N to come in direct contact with the female die members and as the burner O is at all times heating the interior of the male dies or cores, the batter is baked from the inside as well as the outside and thus 115 results in a quick baking of the batter within the dies.

When the cones or other hollow articles are 120 properly baked, the operator takes hold of the operating wheel R and rotates the shaft 125

Q to elevate the male die member and cause the cord or cable X to be wound upon the sheave r, thus drawing up the weight 15 and causing the baffle plate to be moved 5 into the frame A between the female die members and the heating device N, thereby preventing the heat from said heating device N coming in direct contact with said female die members. After the male die 10 members are elevated and the baffle plate thus positioned, the operator depresses the operating lever K against the action of the retractile spring l, causing the gear wheels J to turn and with them the shafts G to 15 which they are secured. In this manner the double levers H are swung from their vertical position toward a horizontal position, whereupon the links I, pivotally secured thereto, act to separate the three sections of 20 the female die members, so as to permit the ready removal of the baked cones or other hollow articles from the concavities in which they are formed. After removal of the finished articles from the female die 25 members, the operator may release the lever K, whereupon the retractile spring l, returns said lever to normal position and causes the sections of each female die member to be brought together, ready for the 30 reception of a further supply of batter into the concavities thereof.

It will be apparent from the foregoing that my invention may be embodied in various modified forms and that changes may 35 be made in the construction of parts without departing from the spirit of my invention or sacrificing any of the advantages thereof.

Having thus described my invention what I claim is,

40 1. In a pastry baking machine, two relatively movable coöperating members, one a male die member and the other a female die member; combined with heating devices arranged above and beneath said die members, 45 and means to prevent the heat coming in contact with one of said die members when said die members are separated.

50 2. In a pastry baking machine, two co-operating die members; combined with a heater, means for separating said die members, and means for preventing the heat of said heater coming in direct contact with said die members when separated.

55 3. In a pastry baking machine, the combination with a frame, coöperating die members relatively movable in a vertical plane to separate the same or bring them together, a heating device for one of said die members, and a baffle plate adapted to be moved 60 between said last-mentioned die member and said heating device when said die members are being separated.

65 4. In a pastry baking machine, the combination with a frame, guide rods rising from said frame and a second frame at the

upper ends of said guide rods, of a die member in said first-mentioned frame, a heating device beneath said die member, a second die member guided on said guide rods for vertical movement toward and from said 70 first-mentioned die member, a baffle plate movable into and out of the space between said first-mentioned die member and said heating device, a shaft on said second frame, operative connection between said shaft and 75 said second die member, operative connection between said shaft and said baffle plate to cause the latter to move into the space between said first-mentioned die member and said heating device, and means for causing 80 said baffle plate to be moved out of said space.

5. In a pastry baking machine, coöperating die members, means for moving one of said die members toward and from the 85 other including a rotatable shaft, a sheave on said shaft, means for rotating said shaft, a heating device in operative relation to the fixed die member, a baffle plate, a cord wound around said sheave and having connection with said baffle plate to cause the latter to move into the space above said heating device when rotating said shaft in one direction, a cord having one end attached to said baffle plate and a weight at 90 attached to its other end, and a pulley around which said last-mentioned cord passes, said weight serving to withdraw said baffle plate from the space above said heating device when said shaft is rotated in an opposite 95 direction.

6. In a pastry baking machine, the combination with a frame, of guide rods in said frame, a die member in said frame having concavities and being separable centrally through said concavities to form a plurality of sections, said sections having said guide rods passed therethrough, and one of said sections being held in fixed position, a shaft passing through said fixed section, a lever secured to said shaft and a link having opposite ends pivotally connected, respectively, to said lever and the movable section of said die member.

7. In a pastry baking machine, the combination with a frame having guide rods therein, a plurality of female die members through which said guide rods are passed, each die member having two parallel rows of concavities formed therein and being separable centrally through said concavities to form three sections, the intermediate section of each die member being held in fixed position on said guide rods and the outer sections being movable toward and from said intermediate section, a shaft passing lengthwise through each intermediate section, a double lever secured to each shaft at each end of each intermediate section, links connecting opposite ends of each double 130

lever with the outer sections of the coöperating die member, a gear wheel secured to each shaft with the gear wheel of the intermediate shaft in mesh with the gear wheels 5 of the other shafts, and means for rotating one of said shafts.

In testimony whereof, I have affixed my

signature in the presence of two subscribing witnesses.

CHARLES STUPIAN.
